CLAIM

The ornamental design for a modular switch assembly, as shown and described.

DESCRIPTION

FIG. 1 is an isometric view of a modular switch assembly showing my new design;

FIG. 2 is another isometric view of the modular switch assembly shown in FIG. 1;

FIG. 3 is a front elevational view of the modular switch assembly shown in FIG. 1;

FIG. 4 is a right side elevational view of the modular switch assembly shown in FIG. 1;

FIG. 5 is a rear elevational view of the modular switch assembly shown in FIG. 1;

FIG. 6 is a left side elevational view of the modular switch assembly shown in FIG. 1;

FIG. 7 is a top plan view of the modular switch assembly shown in FIG. 1; and,

FIG. 8 is a bottom plan view of the modular switch assembly shown in FIG. 1.

The broken lines and the unshaded areas adjacent to them represent portions of the modular switch assembly that form no part of the claimed design.

The cable of the modular switch assembly is shown with a symbolic break in its length. The break lines and the area between the break lines form no part of the claimed design.
